UNITED STATES PATENT OFFICE.

WILSON R. BLOUGH, OF HARRISBURG, PENNSYLVANIA.

DESIGN FOR A BONNET.

40,957.

Specification for Design.

Patented Oct. 25, 1910.

Application filed June 25, 1910. Serial No. 568,943. Term of patent 7 years.

To all whom it may concern:

Be it known that I, WILSON R. BLOUGH, a citizen of the United States, residing at Harrisburg, in the county of Dauphin and State of Pennsylvania, have invented a new, original, and ornamental Design for Bonnets, of which the following is a specification, reference being had to the accompanying drawing, forming part thereof.

The figure is a perspective view of a bonnet, showing my new design.

I claim:

The ornamental design for a bonnet, as shown.

WILSON R. BLOUGH.

Witnesses:
